(57) **CLAIM**

The ornamental design for a step rail for a vehicle, as shown and described.

DESCRIPTION

FIG. 1 is a perspective view of a step rail for a vehicle showing one embodiment of my new design;

FIG. 2 is a front elevation view thereof;

FIG. 3 is a right end view thereof;

FIG. 4 is a left end view thereof;

FIG. 5 is a rear elevation view thereof;

FIG. 6 is a top plan view thereof;

FIG. 7 is a bottom plan view thereof;

FIG. 8 is an enlarged cross-sectional view thereof taken along line 8—8 of FIG. 1, and further is an enlarged cross-sectional view of the embodiment of FIG. 9 taken along line 8—8 of FIG. 9;

FIG. 9 is a perspective view of a step rail for a vehicle showing another embodiment of my new design;

FIG. 10 is a front elevation view thereof;

FIG. 11 is a right end view thereof;

FIG. 12 is a left end view thereof;

FIG. 13 is a rear elevation view thereof;

FIG. 14 is a top plan view thereof; and,

FIG. 15 is a bottom plan view thereof.

The broken line showing of mounting brackets in FIGS. 1 and 9 are for illustrative purposes only and form no part of the claimed design.

The step rail is shown broken away in FIGS. 9—10 and 13—15 to indicate indeterminate length.
